ASH RECEIVER

David Heller, New York, N. Y.

Application March 22, 1937, Serial No. 132,211

8 Claims. (Cl. 131—51)

This invention relates to smokers' articles. More particularly it relates to improved ash-tray construction.

One of the objects of my invention is to provide 5 an ash-tray adapted for use on a table and provided with means for converting the same into a smokers' stand.

Another object of my invention is to provide an 10 ash-tray of the character described, having an extensible support therefor and means for maintaining the support in said extended position.

Still another object of my invention is to provide 15 an ash-tray of the character described, which shall comprise few and simple parts, which shall be easy to assemble, inexpensive to manufacture, which shall be rugged in construction, neat in appearance and yet operate with a high degree of efficiency.

Other objects of my invention will in part be 20 obvious and in part hereinafter pointed out.

These and other features of the invention will be best understood and appreciated from the following description of a preferred embodiment thereof, selected for the purposes of illustration, 25 and shown in the accompanying drawing in which

Fig. 1 is a side elevation, partly sectional, of a 30 ash-tray construction embodying my invention;

Fig. 2 is a cross sectional view taken substantially on the line 2—2 of Fig. 1;

Fig. 3 is a side elevation of the ash-tray shown in Fig. 1, but illustrating the ash-tray in nested, collapsed position; and having parts broken away 35 to disclose the inner construction thereof;

Fig. 4 is a detail view, partly sectional, of a portion of the apparatus shown in Fig. 1;

Fig. 5 is a cross sectional view taken substantially on the line 5—5 of Fig. 4;

Fig. 6 is a cross sectional view taken substantially on the line 6—6 of Fig. 4; and

Fig. 7 is a detail view, partly sectional, of a modified form of extensible support construction.

Referring now in detail to the drawing, and 45 particularly to Figs. 1 and 3, there is disclosed an ash-tray 10 of any desirable shape and size and made of any suitable material generally employed for ash-trays. Into this ash-tray there may be placed the usual removable receptacle (not 50 shown) for removing the ashes therefrom.

By my invention I have provided a construction by means of which the ash-tray 10 may be employed as an ash-tray of the customary table type, and if desired may be converted into a 55 smoker's stand adapted for use on the floor.

To accomplish this, I have provided a base member 11 and an intermediate support 12, interconnecting said base 11 and said ash-tray 10. The support 12 is designed to be extensible, and may comprise a plurality of nestable tubes 15 to 5 19 which may be of any suitable cross sectional contour such as the circular type shown in the drawing, or any other desirable cross sectional shape. The uppermost tube 19 may be permanently attached to the ash-tray 10 as shown, 10 while the lowermost tube 15 may be rigidly fixed to said base member 11. The base 11 may be provided with a hollow portion 20 adapted to be filled with buck shot or any other suitable material to weight the same to provide a substantial 15 base in order to properly support the ash-tray 10 in extended position as shown in Fig. 1. The base 11 may also be provided with a recessed centrally disposed area 25 designed to receive 20 therein the ash-tray 10 to form a neat appearing 20 ash-tray unit for table use when in collapsed or nested position, as shown in Fig. 3. It is noted that the ash-tray 10 is provided with an indented centrally disposed portion 26 surrounding the tube 19 of a size sufficient to clear the tube 15 to 25 permit the nesting of the ash-tray 10 within the base 11. When it is desired to extend the ash-tray 10 from its collapsed position, as shown in Fig. 3, to the extended position shown in Fig. 1, adapted for floor use as a smoker's stand, it is 30 merely necessary to grasp the tray 10 and pull upwardly to extend the nested support 12.

To retain the support 12 in extended position, as shown in Fig. 1, I have provided the following construction: In Figs. 4 to 6 I have shown in detail the construction of the tubular member 16, which is typical of the construction of all the tubes of the support 12. Each tubular member is provided on the outer wall thereof, with a projecting pin 30, and on the inner wall thereof, with 40 a longitudinal groove 31 of predetermined depth, extending from the bottom edge upwardly to a point adjacent the upper edge, where the groove communicates with a second spur groove 32 at an angle to the groove 31. In assembling the 45 support 12, the tube 16 is inserted into the tube 15 from the bottom upwardly with the pin 30 engaging in the groove 31a of the tube 15. It is seen that the projection 30 will strike the upper wall of the groove 32 to limit the upward distance of the movement of the tube 16. If the tube 16 is then turned in a clockwise direction with respect to Fig. 1, the pin 30 will engage in the spur groove 32 and prevent the downward movement of the tube 16 in the tube 15. In a 55

similar manner to that described above, the tube 17 is inserted into the tube 16 and the pin 30a caused to travel in the groove 31 until it reaches the spur groove 32, and upon turning of the tube 17 it will remain locked in open position, and so on with respect to the tubes 18 and 19. If desired, the tube 19 may be a solid rod member. For collapsing the support 12, it is merely necessary to grasp the ash-tray 10 and turn the same 10 in a counter-clockwise direction until all the pins are in alignment with their cooperating grooves, and then press gently downwardly to nest the tubes 15 to 19 and the tray 10 within the base 11.

In Fig. 7 I have shown a modified construction 15 of means for maintaining the support 12 in extended position, comprising a tube 40 disposed transversely of the tube 16a adjacent the bottom edge thereof and attached by such means as soldering, to the inner wall of the tube 16a. The tube 40 is provided with a central wall 41 dividing the tube into two compartments, in each of which is a ball 42, normally pressed outwardly by a spring 43. The balls 42 are adapted to engage in suitably disposed apertures 45 in the walls of the next adjacent lower tube 15a.

If desired, means may be provided for limiting 20 the downward nesting movement of one tube within the other. To this end I have provided on the inner walls of the tubes 16, 17 and 18, slight pin projections 16a, 17a and 18a respectively, 25 which are preferably positioned in the grooves 31, 31a and 31b of the said tubes 16, 17 and 18. It is thus seen that upon collapsing the extensible support 12, the tube 19 will travel downwardly with the pin 30c mounted thereon, in the 30 groove 31b of the tube 18 until the pin 30c abuts the projection 18a in the said groove 31b. Similarly the pins 30b and 30a will be limited in their downward travel by the projections 17a and 16a respectively. The tubes may be provided with the projections 16a, 17a and 18a after or during 35 the operation of assembling the nestable tubes.

In accordance with the provisions of the patent statutes, I have herein described the principle 40 and operation of my invention, together with the apparatus which I now consider to represent the best embodiment thereof, but I desire to have it understood that the apparatus shown is only 45 illustrative and that the invention can be carried out by other means. Also, while it is designed to use the various features and elements in the combination and relations described, some of these may be altered and others omitted without interfering with the more general results outlined, and the invention extends to such use.

Having described my invention, what I claim 50 and desire to secure by Letters Patent is:

1. In combination, an ash-tray, an extensible support, a base and means for attaching said ash-tray to said support, said base being so constructed and arranged that the said support and said ash tray are adapted to be nested within 5 said base.

2. In combination, an ash-tray, an extensible support, a base and means for attaching said ash-tray to one end of said support, said base being so constructed and arranged that the said support and said ash tray are adapted to be 10 nested within said base.

3. In combination, an ash-tray, an extensible support, a base, means for attaching said ash-tray to one end of said support, and means for 15 attaching said base to the other end of said support, said base being so constructed and arranged that the said support and said ash tray are adapted to be nested within said base.

4. In combination, an ash-tray, an extensible 20 support, a base and means for attaching said ash-tray to said support, said support comprising a plurality of nestable members, said base being so constructed and arranged that the said support and said ash tray are adapted to be nested within 25 said base.

5. In combination, an ash-tray, an extensible support, a base, means for attaching one end of said support to said ash-tray, means for attaching the other end of said support to said base, 30 said support comprising a plurality of nestable members, adapted when in nested position to be entirely received in said base.

6. In combination, an ash-tray, an extensible support, a base, a tubular member mounted on 35 said base, means for attaching one end of said support to said ash-tray, said support comprising a plurality of nestable members adapted when in nested position to be entirely received in said tubular member.

7. In combination, an ash-tray, an extensible support, a base, a member mounted on said base, means for attaching one end of said support to 40 said ash-tray, said support comprising a plurality of nestable members adapted when in nested position to be received in said member.

8. In combination, an ash-tray, a base, an extensible support comprising a plurality of nestable members, the first of said nestable members being fastened to said ash-tray, the last of said 45 nestable members being fastened to said base, said support, when in nested position being adapted to be received in said last of said nestable members.

DAVID HELLER.
